Des. no. 20,208

UNITED STATES PATENT OFFICE.

ISAAC DE HAVEN, OF ALLEGHENY, PENNSYLVANIA.

DESIGN FOR A HEATING-STOVE.

SPECIFICATION forming part of Design No. 20,208, dated October 21, 1890.

Application filed June 10, 1890. Serial No. 354,963. Term of patent 7 years.

To all whom it may concern:

Be it known that I, ISAAC DE HAVEN, a citizen of the United States, residing at Allegheny, in the county of Allegheny and State of Pennsylvania, have invented a Design for Heating-Stoves; and I do hereby declare the following to be a full, clear, and exact description of the invention, such as will enable others skilled in the art to which it appertains to make and use the same, reference being had to the accompanying drawing, and to the letters of reference marked thereon, forming part of this specification.

The photograph is a perspective view of a stove illustrating my design. The latter includes the base or bottom portion and the doors, as hereinafter specified. The foot or base section A has plain feet at the corners and rosette-shaped ornaments at the top of the feet, with intermediate bands of scroll and fluting work, as shown at A. Upon this is a base-plate B, provided with an ogee molding ornamented with a band of shell-work. Upon this base-plate is a square ash-pit section ornamented in the center of each of the three closed sides with a shell of fluted work flanked at each side of fluting with scroll-work, and provided with foliate-work at each of the four corners, as shown at C C. The upper part of said base having a molding of fine shell-work D extending around its four sides. In front of ash-pit section is an ash-pit door E, ornamented with scroll and foliate work on the portion in which the sliding register is arranged. The foot-rails F on the sides of the base are approximately semi-elliptical in form and rounded on the outer side and ornamented with transverse corrugations, while the curved upwardly-extending arms are ornamented by sprays of foliate-work. The door-frame G consists of a square frame of molding filled in with a band of ornamental shell-work, and surmounted at the upper part with the name of the stove interwoven with scroll-work, and provided at the bottom with a band of similar scroll-work. The feed-door H is attached to this door-frame by hinges, and consists of a plain molding standing boldly out from the door-frame

and ornamented on its outer face with shell 50 molding to correspond with that on the door-frame. Said feed-door has a mica frame in its center having upright and transverse slats with scroll-slats intervening therewith.

The third part of my invention consists of 55 the top-ring of the stove J, having a heavy plain edge at bottom curving upward and inward to a point where it joins the dome top in the form of a round molding, said ring top having a heavy band of fluting or corrugations running around its central part. The top K is dome-shaped, having a band of scroll-work ornamentation running around its central part, and the whole surmounted with an ornamental urn L. 60

What I claim is—

1. The design for the foot or base section of the stove, composed of the feet, the rosette-shaped ornaments above the feet, and scroll and fluting work extending along the base 70 intermediately of such corner ornaments, as shown.

2. The design for the base-plate of a stove, composed of the ogee molding having a bead of shell-work, as shown. 75

3. The design for an ash-pit section of a stove, composed of fluting arranged centrally on each of three closed sides, scroll-work flanking such fluting, and foliate-work arranged laterally from the latter at each of the four corners of the ash-pit, as shown. 80

4. The design for the ash-pit door E of a stove, the same being composed of scroll and foliate work, as shown.

5. The design for the foot-rail F of a stove, 85 composed of the curved body having corrugations and the curved arms having foliate-work, as shown.

6. The design for the door-frame of a stove, composed of the square molding ornamented 90 with bands G of scroll-work arranged at top and bottom, as shown.

7. The design for the feed-door H of a stove, consisting of a plain square molding standing out in bold relief and ornamented with 95 a beading of shell-work, and the central open-work portion composed of the central disk, the four radial straight bars arranged verti-

OVER

eally and horizontally, and the scrolls diverging from said disk diagonally, as shown.

8. The design for a stove, consisting of the base A, base-plate B, ash-pit section C, foot-
5 rail F, the molding and door H, the top-ring J, and domed top K, having the scroll, foliate, and other ornamentation, as shown and de-
scribed.

In testimony whereof I sign this specification, at Allegheny, Pennsylvania, this 7th day 10
of May, A. D. 1890, in the presence of two wit-
nesses.

ISAAC DE HAVEN.

Witnesses:

JOHN A. ROE,
PHILIP MAURY.
